UNITED STATES PATENT OFFICE.

CHARLES FOHMAN, OF CLEVELAND, OHIO, ASSIGNOR TO THE THEODOR KUNDTZ COMPANY, OF CLEVELAND, OHIO, A CORPORATION OF OHIO.

DESIGN FOR A DOUBLE PEDESTAL FOR A COMBINED SCHOOL DESK AND CHAIR.

52,872.

Specification for Design.

Patented Jan. 14, 1919.

Application filed May 8, 1918. Serial No. 233,396. Term of patent 14 years.

To all whom it may concern:

Be it known that I, CHARLES FOHMAN, a citizen of the United States, residing at Cleveland, in the county of Cuyahoga and State of Ohio, have invented a new, original, and ornamental Design for a Double Pedestal for a Combined School Desk and Chair, of which the following is a specification, reference being had to the accompanying drawing, forming part thereof.

Said drawing is a perspective view of a

double pedestal for a combined school desk and chair showing my new design.

I claim:

The ornamental design for a double pedestal for a combined school desk and chair substantially as shown.

CHARLES FOHMAN.

Witnesses:

HENRY BORNES,
JOSEPH PIMSAER.
